(57) **CLAIM**

The ornamental design for a display screen or portion thereof with graphical user interface, as shown and described.

DESCRIPTION

The patent file contains at least one drawing executed in color. Copies of this patent with color drawings will be provided by the Office upon request and payment of the necessary fee.

FIG. 1 is a front view of a first embodiment of a display screen or portion thereof with graphical user interface showing our new design; and,

FIG. 2 is a front view of a second embodiment of a display screen or portion thereof with graphical user interface showing our new design.

The outermost broken line perimeter in the drawings illustrates a display screen or portion thereof. All other broken lines in the drawings illustrate portions of the graphical user interface. The aforementioned broken line subject matters do not form part of the claimed design.
